NECKTIE RACK

Clarence F. Brey, New York, N. Y.

Application June 25, 1935, Serial No. 28,301

5 Claims. (Cl. 211—120)

This invention relates to racks intended more particularly for neckties and similar articles.

The aim of my invention is to provide a simple and compact rack capable of accommodating a multiplicity of neckties or the like suspended in a row for convenience of ready selection between them, and with facility for easy insertion and removal individually without necessitating disturbance of any of the others.

10 One way in which the foregoing and other advantages may be readily realized in practice will appear from the following detailed description of the attached drawing, wherein Fig. I shows the front elevation of a necktie rack conveniently embodying the present improvements.

Fig. II is a fragmentary view on an enlarged scale showing the front elevation of one end of the rack.

Fig. III is a cross section taken as indicated by the arrows III—III in Fig. II; and

20 Fig. IV is a view, partly in plan and partly in longitudinal section, taken as indicated by the arrows IV—IV in Fig. II.

In the form illustrated, the necktie rack of my invention comprises two axially-aligned horizontal helices 1 and 2 fashioned from relatively stout spring wire; and an attaching bar 3 for supporting said helices, said bar being pierced adjacent its opposite ends for passage of screws 4 whereby the rack may be fastened to any vertical surface such as a wall or a door. The helix 1, it will be noted, is of coarse pitch so that comparatively thick neckties T can be accommodated in a row between its convolutions; while the helix 2 is of a finer pitch to accommodate thinner ties T' between its convolutions. Incident to placement in the rack, the ties T and T' are doubled upon themselves and the two folds inserted edge-wise respectively in two adjacent intervals of the helices 1 and 2. After being so engaged, the ties T and T' are given a quick downward pull as far as permitted by engagement of their folds or creases with the tops of the convolutions of the helices 1 and 2 intervening the extremities of said ties, and thereby leveled in the rack.

The attaching bar 3 is herein shown as being of composite construction, and as consisting of a pair of superimposed components 5 and 6 of narrow strip metal which are permanently united at their opposite ends by securing means in the form of screws 7. The bar component 6 is laterally offset for the greater part of its length as at 8, with provision of a vertical longitudinal interval 9 in which the convolutions of the two helices 1 and 2 are firmly engaged at one side, see

Fig. III, with freedom however, to expand and contract lengthwise as the ties are inserted between, or withdrawn from between their convolutions. Near its opposite ends, the bar component 5 is provided with short longitudinal slots 10 and 11 which are respectively engaged by the remote outwardly-turned ends 12 and 13 of the helices 1 and 2. A similar slot 14 at an intermediate point in the bar component 5 is engaged by the contiguous outwardly turned ends 15 and 16 respectively of the helices 1 and 2. By virtue of this construction, the coils 1 and 2 are constrained against rotation in the bar 3, while being permitted to expand and contract, as hereinbefore explained, within the limits of the slots 10, 11, and 14.

As an alternative, the two helices may be made as one from a single length of wire by controlling the winding such that a part of the coil is given a coarse pitch, and the remainder a closer pitch in simulation of the arrangement shown in Fig. I. In the latter event the intermediate slot 14 in the bar component 5 may be dispensed with, but the single coil provided with laterally turned ends (like those shown at 12 and 13 in Fig. I) to engage the slots 10 and 11 at the ends of said bar component.

From the foregoing it will be seen that I have provided a simple, compact and inexpensive rack capable of supporting a row of suspended neckties or the like in definite separation and in close contiguity in such manner that they can be readily selected from and easily removed and inserted individually without disturbing any of the others.

Having thus described my invention, I claim:

1. A rack for neckties and the like comprising a horizontal helix of spring wire with convolutions spaced to receive between them relatively thick ties; a second helix, likewise of spring wire, but with closer spaced convolutions for reception between them of relatively thin ties; and means for supporting the two helices in axial alignment with capacity for independent endwise expansion and contraction.

2. A rack for neckties and the like in accordance with claim 1, wherein the supporting means is in the form of a bar with a vertical longitudinal slot in which the convolutions of the two helices are slidably engaged at one side.

3. A rack for neckties and the like in accordance with claim 1, wherein the supporting means is in the form of a bar with a vertical longitudinal slot in which the convolutions of the two helices are slidably engaged at one side, and with short horizontal slots respectively at the

ends and at an intermediate point for engagement by laterally turned end portions of the coils.

4. A rack for neckties and the like comprising two horizontal coil sections of spring wire forming a helix, one with convolutions spaced laterally for reception between them of relatively thick ties, and the other with closer spaced convolutions for reception between them of relatively thin ties; means for supporting the helix with capacity to expand and contract endwise; and a supporting bar with a vertical longitudinal interval in which the convolutions of the helix are slidingly engaged at one side.

5. A rack for neckties and the like comprising two horizontal coil sections of spring wire form-

ing a helix, one with convolutions spaced laterally for reception between them of relatively thick ties, and the other with closer spaced convolutions for reception between them of relatively thin ties; means for supporting the helix with capacity to expand and contract endwise; and a supporting bar with a vertical longitudinal interval in which the convolutions of the helix are slidingly engaged at one side, said bar also having longitudinal slots in which laterally turned end portions of the helix are engaged with capacity for limited movement to permit lengthwise expansion of the sections.
